MILK BOTTLE HOLDER

William R. Browder, Evansville, Ind., assignor
of one-third to William S. Stateler, Evansville,
Ind.

Application September 13, 1938, Serial No. 229,762

10 Claims. (Cl. 232—41)

The present invention relates to milk bottle holders and has for its primary object to provide a device of this character adapted for conveniently mounting in position upon a supporting structure and embodying a pair of milk bottle receiving openings adapted to engage the neck of the milk bottle together with means for locking the bottles in position in the holder.

A further object of the invention is to provide an apparatus of this character embodying an audible alarm adapted to be sounded upon the placing of a bottle in position in the holder.

Another object is to provide a device of this character of simple and practical construction, which is efficient and reliable in performance, relatively inexpensive to manufacture and maintain in operative position and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which

Figure 1 is a top plan view.

Figure 2 is a similar view with the cover removed.

Figure 3 is a sectional view taken substantially on a line 3—3 of Figure 1.

Figure 4 is a perspective view of the rear locking member, and

Figure 5 is a similar view of the intermediate keeper member adapted for successive engagement by the rear locking member of the respective locking mechanisms.

Referring now to the drawings in detail, wherein for the purpose of illustration I have disclosed a preferred embodiment of the invention, the numeral 5 designates a bottle supporting plate having an upstanding rear edge 6 providing means for suitably attaching the device in position upon a supporting structure, such as for instance a door jamb or side of the wall of a building.

The front edge of the plate 5 is formed with a pair of rearwardly extending notches 7 adapted to receive the neck of a milk bottle as indicated by the dotted lines at 7' in Figure 2 of the drawings.

Adjacent the side edges of each of the notches 7 is a bottle locking mechanism, the mechanism being of identical construction for each notch and accordingly, a detailed description of one

The locking mechanism comprises a pair of keeper plates 8 and 9 pivotally mounted at one end upon a pin 10 carried by the plate 5 and positioned adjacent the end portion of the plate, said keeper plates being arranged flatwise with respect to each other and in spaced vertical relation and with one longitudinal edge of each of said plates of arcuate form as shown at 11 and 11' and terminating adjacent one of the edge portions of the notch 7, the edge of the plate 10 9, at its inner end overlying said notch, as will be apparent from an inspection of Figure 2 of the drawings.

Coil springs 12 and 12' are carried by the pin 10, each having an end portion engaging an outer longitudinal edge of the respective plates 8 and 9 for yieldably urging said plates in a direction toward the adjacent notch.

The plate 8 is formed with a finger 13 at its free end portion provided with a shoulder 14 against which is seated a lug 15 carried at one end of a catch 16, said catch pivotally mounted at its end adjacent the lug 15, as shown at 17, and said catch is provided with a laterally extending projection 18 against which a stop 19 is adapted to engage to limit the movement of the plate 9 relative to the notch 7. The free end portion of the plate 9 is also formed with a notch 20 within which the end of the projection 18 is adapted to enter upon an outward pivotal movement of said plate. The plate 8 is designed for engagement by the lip of a milk bottle when inserted in the notch 7, while the plate 9 is engaged by the neck of the bottle. Movement of the plate 8 by the lip of the bottle releases the finger 13 from the lug 15, while at the same time the neck of the bottle releases the plate 9 from engagement with the projection 18 to permit subsequent movement of the catch 16 when the bottle engages the plate 21. The two plates 8 and 9 serve as a duplicate releasing means to insure proper functioning of the device and the plate 9 further serves to support the lip of the bottle when the same is resting in the notch 7. The double releasing plates further prevent unauthorized manipulation of the device by the insertion of a person's finger in the notch. The proper throw of the plates 8 and 9 to effect releasing movement is dependent on their engagement by the neck and lip of a bottle of predetermined size

and accordingly, it would be extremely difficult to manipulate the plates exactly by any other instrumentality and at the same time release the catch 16 in order that the locked bottle may be removed.

The catch 18 is also provided with a laterally extending bottle contacting plate 21 having its free edge overlying the rear portion of the notch 7, the opposite edge of said plate having an upstanding flange 22 adapted for engagement by one end of a leaf spring 23 which is pivotally secured intermediate its ends as at 24 to the attaching plate 6.

At the side of the notch 7 opposite from the plates 8 and 9 is positioned a bottle locking plate 25 fixed intermediate its ends to a pin 26 rockably mounted in the plate 5 and having an arcuate edge 27 adapted to embrace a side of the milk bottle opposite from the plates 8 and 9 and cooperating with said last named plate to secure the bottle in position within the notch 7.

The opposite end portions of the bottle engaging plate 25 overlie the notch 7, the outer end 28 being substantially free of the notch when in bottle releasing position while the inner 29 thereof substantially overlies the notch as clearly shown at the left hand side of Figure 2 of drawings.

Substantially at the center of the plate 5 is positioned a pivot pin 30 upon which a catch locking member 31 is pivotally mounted intermediate its ends, the rear end of said member 31 having a notch 32 for receiving an angularly extending finger 33 formed on the free end of the latch 16. Arising from the member 31 is an upstanding lug 36 adapted for engagement by the free end portion of a leaf spring 35 which is fixedly secured to the pin 26, said pin being fixed to the bottle locking plate 25 for rotary movement in accordance with the pivotal action of said plate. A spring 36 extends from the pin 30 to the pin 26 to prevent idle movement of the locking plate 25.

The rear edge of the plate 25 is also formed with a shoulder 37 adapted for engagement with the forward end portion of the member 31 when the plate member 25 is in bottle locking position.

A cover plate 38 is secured on posts 39 which have threaded bores 40 in the top portion thereof for receiving screws 41 to secure the cover plate in position, the pivot pins 10 and 17 being freely inserted through the lower portion of said openings.

Secured to the upstanding pin 30 is a bell 42 for engagement by a clapper 43 secured by an arm 44 to a rotating member 45 pivoted on a pin 46 carried by the plate 5. A lug 47 is pivotally carried by the member 45 and depends therefrom in the path of an arm 48 projecting from the front end of the member 31. The lug 47 is yieldably held in a downwardly extending position by a spring 49 and the member 45 is yieldably held against rotation in one direction by a spring 50. A stop 51 also extends upwardly from the plate 5 for engagement by a projection 52 carried by the member 45.

In the operation of the device the locking mechanism at one side of the plate is always in bottle locking position while the locking mechanism at the opposite side thereof is in bottle releasing position. In the present instance, and with particular reference to Figure 2 of the drawings, the locking mechanism on the right hand side of the plate is shown with a bottle locked in position therein, while the locking mechanism at the left hand side of the plate is shown ready to receive a bottle therein.

To the under side of the cover plate 38 is secured one end of a spring arm 53, the opposite end of the arm extending rearwardly in a posi-

tion overlying the notch 7 as shown by the dotted lines in Figure 2 and the rear end of the arm is bent angularly downwardly for engagement behind the flange 22 of the latch releasing plate 16. Accordingly, when a bottle is inserted in the notch at the left hand side of the plate the upper edge of the bottle will engage the arm 53, releasing the same from the plate 21 and upon contact of the bottle with the plate 9 and with the rear end 29 of the plate 25, said plates will be swung into a position as shown at the right hand side of Figure 2, such movement of the plate 25 causing the spring 35 to engage the lug 34, for turning the member 31 into a position for the engagement of its rear end by the catch 16 at the right hand side of the locking mechanism when the member 31 has been released by the contact of the bottle with the plate 21. The pivotal movement of the plate 9 by reason of its engagement with the bottle will likewise enable the projection 18 to enter the notch 20 to permit the pivotal movement of the catch 16 when the bottle subsequently engages the plate 21 and the plate 8 will similarly be disengaged from the lug 15.

This movement will also release the member 31 from the shoulder 37 of the locking plate on the right hand side of the device and engage the locking plate on the left hand side to permit bottle releasing movement of the former and bottle locking movement of the latter.

When the bottle at the right hand side of the device has been removed, the plate 9 will swing inwardly toward the notch 7 which, by reason of its engagement with the projection 18 will pivot the catch 16 to enable engagement of the finger 33 in the notch 32 of the member 31.

The plate 8 is positioned for engagement by the lip of the bottle while the plate 9 is engageable by the bottle neck.

Such movement of the member 31 will likewise cause the sounding of the alarm comprising the bell 42.

It is believed the details of construction and manner of operation of the device will be readily understood from the foregoing without further detailed explanation.

Having thus described the invention, what I claim is—

1. A bottle lock comprising an attaching plate having a pair of bottle receiving notches, duplicate locking mechanisms carried by the plate adjacent the notches and arranged for opposite locking and unlocking movement and means operable through the medium of a bottle inserted in one of the notches and extending circumferentially at opposite sides of the bottle for engagement by the neck as well as the lip of the bottle for releasing one of said locking mechanisms and locking the other locking mechanism.

2. A bottle lock comprising an attaching plate having a pair of bottle receiving notches, duplicate locking mechanisms carried by the plate adjacent the notches and arranged for opposite locking and unlocking movement and including a swingably mounted horizontal bottle neck engaging plate adjacent each notch, a common catch locking member lockably engageable at one end with said last named plates, individual catch members for the other end of said common catch locking member and a plurality of locking plates for the individual catch members and controlled by contact by the neck and lip of a bottle inserted in said notches.

3. A bottle lock comprising an attaching plate having a pair of bottle receiving notches, dupli-

- cate locking mechanisms carried by the plate adjacent the notches and arranged for opposite locking and unlocking movement and means operable through the medium of a bottle inserted in a horizontal direction in one of the notches for moving one locking mechanism into locking engagement with the inserted bottle and releasing the other locking mechanism, said means comprising a plurality of spring actuated circumferential bottle engaging plates pivotally mounted adjacent the respective notches and arranged for successive engagement by the bottle during horizontal inserting movement.
4. A bottle lock comprising an attaching plate having a pair of bottle receiving notches, duplicate locking mechanisms carried by the plate adjacent the notches and arranged for opposite locking and unlocking movement and means operable through the medium of a bottle inserted in one of the notches for moving one locking mechanism into locking engagement with the inserted bottle and releasing the other locking mechanism, said means comprising a plurality of spring actuated bottle engaging plates pivotally mounted adjacent the respective notches and arranged for successive engagement by the bottle during inserting movement, certain of said bottle engaging plates having interlocking engagement with each other.
- 30 5. A bottle lock comprising an attaching plate having a pair of bottle receiving notches, duplicate locking mechanisms carried by the plate adjacent the notches and arranged for opposite locking and unlocking movement and means operable through the medium of a bottle inserted in one of the notches for moving one locking mechanism into locking engagement with the inserted bottle and releasing the other locking mechanism, said means comprising a plurality of spring actuated bottle engaging plates pivotally mounted adjacent the respective notches and arranged for successive engagement by the bottle during inserting movement and means carried by certain of the adjacent bottle engaging plates for lockably engaging the same.
- 35 6. A bottle lock comprising an attaching plate having a pair of bottle receiving notches, duplicate locking mechanisms carried by the plate adjacent the notches and arranged for opposite locking and unlocking movement and means operable through the medium of a bottle inserted in one of the notches for moving one locking mechanism into locking engagement with the inserted bottle and releasing the other locking mechanism, said means comprising a plurality of spring actuated circumferential bottle engaging plates pivotally mounted adjacent the respective notches and arranged for successive engagement by the bottle during inserting movement and means engageable with a plate of each locking mechanism for alternately retaining the mechanisms in locked position.
- 40 7. A bottle lock comprising an attaching plate having a pair of bottle receiving notches, a pair of duplicate locking mechanisms carried by the plate adjacent the notches and arranged for opposite locking and unlocking movement, each of said mechanisms including means operable through the medium of a bottle inserted in one of the notches for moving one locking mechanism into locking engagement with the inserted bottle and releasing the other locking mechanism,
- 45 and said means comprising a plurality of spring actuated bottle engaging plates pivotally mounted adjacent the respective notches and arranged for successive engagement by the bottle during inserting movement and a catch member releasably engaged by said plates, a bottle-actuated bottle-locking plate pivoted adjacent each notch and a pivoted catch locking member providing a locking connection between the catch member of one mechanism and the locking plate of the other mechanism.
- 50 8. A bottle lock comprising an attaching plate having a pair of bottle receiving notches, and duplicate locking mechanisms carried by the plate adjacent the notches and arranged for opposite locking and unlocking movement, each mechanism comprising a plurality of bottle engaging plates pivoted to the attaching plate with a portion movable into and out of overlying position with respect to a notch and including a pair of vertically spaced plates engageable respectively by the neck and lip of a bottle for simultaneous actuation of the pair of plates, a bottle actuated catch releasably engaged at one end by said pair of plates and a plate locking member releasably engaged by the other end of said catch.
- 55 9. A bottle lock comprising an attaching plate having a pair of bottle receiving notches, and duplicate locking mechanisms carried by the plate adjacent the notches and arranged for opposite locking and unlocking movement, each mechanism comprising a plurality of bottle engaging plates pivoted to the attaching plate with a portion movable into and out of overlying position with respect to a notch and including a pair of vertically spaced plates engageable respectively by the neck and lip of a bottle for simultaneous actuation of the pair of plates, a bottle actuated catch releasably engaged at one end by said pair of plates, a plate locking member releasably engaged by the other end of said catch, a catch releasing plate for each mechanism, and means carried by the last named plate of each mechanism for oppositely actuating said member into and out of locking engagement with the opposite releasing plate and with said catch.
- 60 10. A bottle lock comprising an attaching plate having a pair of bottle receiving notches, and duplicate locking mechanisms carried by the plate adjacent the notches and arranged for opposite locking and unlocking movement, each mechanism comprising a plurality of bottle engaging plates pivoted to the attaching plate with a portion movable into and out of overlying position with respect to a notch and including a pair of vertically spaced plates engageable respectively by the neck and lip of a bottle for simultaneous actuation of the pair of plates, a bottle actuated catch releasably engaged at one end by said pair of plates, a plate locking member releasably engaged by the other end of said catch, a catch releasing plate for each mechanism, and means carried by the last named plate of each mechanism for oppositely actuating said member into and out of locking engagement with the opposite releasing plate and with said catch, a cover for the mechanisms overlying the notches in spaced relation therefrom and a bottle actuated locking member carried by the cover and releasably engageable with the catch.

WILLIAM R. BROWDER.
